BOTTLE STOPPER

Harry Thomas, Lancaster, Pa., assignor to Armstrong Cork Company, Lancaster, Pa., a corporation of Pennsylvania

Application July 27, 1936, Serial No. 92,731

2 Claims. (Cl. 215—48)

This invention relates to bottle stoppers and more particularly to a metal covered wood top stopper; and to a metal covered wood top stopper head, as an article of manufacture.

5 It is an object of my invention to provide a stopper top having a metal covering sheath which is firmly attached to the head member and secured against relative rotation with respect thereto. In one embodiment of my invention, the 10 cut edge of the metal is embedded in the wood of the top and is thereby concealed and protected against corrosion. This structure provides an effective interlocking of the component elements and produces a structure in which the sheath is 15 attached to the head member without objectionable knurling or folding of the skirt portion.

Another object of my invention is to provide a stopper top which may be decorated or embossed on the top or skirt portions thereof.

20 The article of my invention is a stopper top in which a metal covering or sheath is disposed over the head member and the edge of the skirt of the sheath is turned into a bead grippingly engaging the head and clamping the same in the region of 25 the periphery thereof between the bead and the top of the sheath. My invention also contemplates the combination of such a stopper top with a seal such as a cork to form a closure for bottles or other receptacles.

30 My method is directed generally to the formation of stoppers and stopper tops in which a metal covering sheath for the head member is beaded so as to grippingly engage the head member and prevent relative rotation between the component 35 parts forming the top. My method is adapted to be carried out in a simple assembly machine in which the beading operation is effected by means of a curling die or punch.

Certain preferred embodiments of my invention 40 will be described in connection with the attached drawings in which

Figure 1 is a side elevation of a stopper including a metal covered head portion;

Figure 2 is a sectional view on the line II—II 45 of Figure 1;

Figure 3 is a sectional view showing a modified stopper head embodying my invention;

Figure 4 is a top plan view showing a modification of my invention; and

50 Figure 5 is a vertical sectional view on the line V—V of Figure 4.

In the embodiment shown in Figures 1 and 2, the bottle stopper comprises a cork 2, and a wood head member 3 which is flanged at 4 so as to extend radially outwardly from the periphery of

the cork 2. The head member may be formed with a projecting boss 5 adapted to be positioned within a recess provided in the cork 2, although the particular shape of the head may be modified to suit any particular requirements. A stratum of adhesive 6 disposed about the periphery of the boss 5 and in an annular recess 7 provided in the head member 3, serves to secure the stopper and the head member as a unit. The boss 5 serves to reinforce the cork in the region of greatest stress resulting from the application of torque to the stopper in removal thereof from a bottle to which the stopper is applied. The wood head 3 has a domed top 8 and a slightly flared skirt 9. A metal cover or sheath is disposed over the head member 3 with its top 10 lying in engagement with the top 8 of the head member and its skirt 11 lying in engagement with skirt 9 of the head member. The lower edge of the skirt 11 is turned into a rounded, inwardly and upwardly extending bead 12 with the cut edge 13 thereof penetrating to a material depth within the body of the head member 3. The bead is spaced radially, outwardly from the periphery of the stopper 2 a distance sufficient to accommodate the lip of a bottle.

By beading the sheath so that the cut edge thereof penetrates the body of the head member, a firm frictional interlocking of the head and sheath is obtained and relative rotation inhibited. In addition, the cut edge is adequately protected against rusting or corroding. It has been common practice in the manufacture of metal-covered, wood-topped stoppers to knurl or otherwise mechanically interlock the skirt of the sheath with the skirt of the head member. If the knurling is not properly formed, relative rotation of the component elements results upon the application of turning stress in removal of the stopper from the container it seals. The edge of the sheath has generally been folded under the head portion of the stopper top and the cut edge thereof has either been left exposed or thrust into the cork thus weakening it in the area of greatest stress. Furthermore, the puckering of the metal incident to folding of the skirt under the head member is objectionable from an appearance standpoint because it prevents the closure from fitting closely against the lip of the bottle to which it is applied.

In Figure 3 a modified stopper top is shown in which the wood head member 14 is provided with a stopper receiving recess 15, and in which the edge 16 of the skirt of the sheath is formed into a rounded bead which extends generally inwardly and upwardly and, as in the other embodiment,

grippingly clamps the head member 14 between the top 17 of the sheath and the portion 18 of the head 16. It will be observed that the cut or raw edge 19 of the metal sheath is concealed and 5 is protected against corrosion.

In carrying out my method, I prefer to form the head member with the grain thereof running along a direction substantially parallel to the axis of the head member. A metal sheath is then 10 formed. This sheath may be decorated prior to formation into a cap or cup shape. The inner diameter of the metal sheath is preferably substantially the same as the outer diameter of the head member, and it is desirable to have the top 15 of the sheath conform generally to the top of the head member in order that maximum frictional engagement of the two elements will be obtained and deformation of the sheath will be obviated. The skirt of the sheath should be somewhat longer 20 than the skirt of the head member and, upon telescoping of the head member within the sheath, the skirt should extend below the skirt of the head member a distance sufficient to permit the formation of a bead. The bead is preferably 25 formed by positioning the telescoped sheath and head member within a die member having a cavity which conforms closely to the configuration of the sheath and, while so supported, urging the extending portion of the skirt of the sheath into 30 an inwardly and axially directed bead by means of a curling or beading punch so shaped as to dispose the cut edge within the body of the head member, as shown in Figure 1, or to curl the edge outwardly, as shown in Figure 3. Curling 35 punches are common to the closure industry and are known to those skilled in the art.

My invention is applicable to sheathings which are embossed on either the top or skirt portions or both. If the top portion be embossed, as shown 40 in Figures 4 and 5, where the letter "A" within a circle has been embossed in the head portion 10 of the sheath so as to provide upstanding portions 19 and 20, it may be found desirable to position a layer of resilient material 21 between the 45 top 10 of the sheath and the top 3 of the head in

order that the embossing will not be stretched upon the beading operation, but will accommodate itself by compressing the resilient layer disposed between the sheath and the head member. A thin layer of cardboard or a cork disk may be 5 used for this purpose.

The trend at the present time is toward smooth skirted closures, and my invention permits the use of such skirt formation while firmly securing the head member and sheath against relative rotation. By practicing my invention, the assembly operation is simplified; it requires only a beading or curling punch as contrasted with the complicated knurling and folding equipment heretofore required. Thus, economy of manufacture is 10 derived from the use of my invention, as well as the production of a superior product, both from the point of view of utility and of design.

While I have described and illustrated certain preferred embodiments of my invention, it will 20 be understood that the invention is not so limited but may be otherwise embodied within the scope of the following claims.

I claim:

1. As a new article of manufacture, a bottle 25 stopper comprising a stopper top having a wooden head member with the grain thereof disposed substantially normal to the top thereof, a resilient element of sheet-like form disposed in engagement with the top of said wooden head member, a sheet metal sheath having top and skirt portions covering said resilient member and the peripheral edge portion of said head member, the free edge of said skirt being disposed as an inwardly and upwardly directed rounded bead, with 30 the terminal edge of said sheath penetrating said head member in a direction parallel to the grain thereof along a line disposed radially inwardly from the periphery of said head member, said resilient element being under compression.

2. A stopper top in accordance with claim 1 in which the top portion of the covering sheath is nonplanar and the resilient element is nonuniformly compressed.

HARRY THOMAS.
